UNITED STATES PATENT OFFICE.

CHARLES W. DAVIS, OF EDGEWORTH, PENNSYLVANIA, ASSIGNOR TO STANDARD UNDERGROUND CABLE COMPANY, OF PITTSBURGH, PENNSYLVANIA, A CORPORATION OF PENNSYLVANIA.

TERMINAL STRUCTURE.

1,021,453.

Specification of Letters Patent. Patented Mar. 26, 1912.

Application filed July 1, 1909. Serial No. 505,381.

To all whom it may concern:

Be it known that I, CHARLES W. DAVIS, residing at Edgeworth, in the county of Allegheny and State of Pennsylvania, a citizen of the United States, have invented or discovered certain new and useful Improvements in Terminal Structures, of which improvements the following is a specification.

10 My invention relates to improvements in the construction of terminals for metal-sheathed electrical cables, and its object is simplicity of structure, thoroughness of insulation, and simplicity in assembling.

15 The accompanying drawing which forms part of this specification shows in vertical section a terminal structure embodying my present invention.

The invention is peculiarly applicable to, 20 although not necessarily limited to, use in the installation of high voltage installations.

The terminal structure in which my invention resides consists essentially of a case 25 or shell 1, formed preferably entirely of insulating material. In form this case or shell is perforate from end to end, its inner bore preferably enlarging from the end which receives the metal sheathed cable to a 30 larger chamber, indicated in the drawings at 2. Externally, this sleeve-like body is provided with one or more petticoats 3, formed preferably of insulating material. It is closed at the end opposite to that at 35

which the cable is introduced by a cap 4, formed preferably of insulating material, and preferably extending beyond the body of the casing 1, to form another petticoat 5. The opposite end of this casing 1, that is the 40

end into which the metal-sheathed cable is to be introduced, is provided with means for making secure connection with the metallic cable sheath at a point adjacent to the entrance of the cable into the perforation in 45 the casing. To this end, a screw thread 6 may be formed upon the outer surface of casing 1 adjacent to the extremity thereof, such screw thread being conveniently formed in a metallic sleeve within which

50 the body of the casing is molded, or which is otherwise secured thereon by a tight joint. Engaging the casing 1 at this point, as by a corresponding screw thread, is a metallic thimble 7, which when in place 55 protrudes from the end of the casing 1, and

upon which secure and rigid joint may be made to the cable sheath, as by a wiped-solder joint indicated at 8.

The structure thus described is arranged to be installed in vertical position, and preferably the cable will be led in at the lower end, the cap 4 forming the upper end of the structure. In such an arrangement, the petticoat projections 3 and 5 which have been described extend downwardly as well 60 as outwardly, so that when exposed to the weather the nether surface of each petticoat will afford a dry and leakage-preventing area. Furthermore, the joint between the body or shell 1 and the thimble 7 may be 65 protected by a similar petticoat 9. The number of petticoats 3 is determined by the number of separate conductors which the cable contains to which the particular terminal is to be applied and which are to be 70 led out separately, each being protected against leakage to and from the others. The petticoats 3 and 5 together form protection, each for a single lead-out. In the drawing there are two petticoats 3 and one 75 petticoat 5, making three in all, and the cable shown is a three-strand cable, and each strand is led out separately, each through a lateral hole in the wall of the casing arranged each beneath a different 80 one of the petticoats specified. It will be seen that each lead-out is thus protected by a petticoat with its dry leakage-preventing surface.

The lead-out conductors 10 may conveniently be of rubber-covered wire engaging the exposed cable conductors within the enlarged chamber of casing 1, the particular form of joint forming no part of my present invention, but being of any form preferred 90 and known to the art. The rubber-covered lead-out wire will fit snugly within the orifice through which it is passed; and, to make a weather-tight joint, before the cover 4 is applied, the space within the terminal structure may be filled with an insulating substance applied in liquid form. When the connections have been made and the space within the structure thus filled, the application of the cover plate 4 closes in the whole 95 100 and makes a complete weather-resisting structure.

In my Patent No. 898,097 I have shown a terminal structure which has certain features of resemblance to this; notably in hav- 110

ing a series of petticoats one above the other, beneath each of which a conductor is led out, but it will be observed on referring to that patent that in it the conductors are molded in the insulating material which forms the petticoated body, and that the chamber in which the connections are made is not within the petticoated body, but within the part which in this specification I have designated a thimble.

It will be observed that the petticoat 9 which protects the screw-threaded connection 6 between the body 1 and the thimble 7, also serves as a leakage-preventing device between the leads-out and the metallic cable sheath.

I claim herein as my invention:

1. A terminal structure for metal-sheathed cables which consists of a body portion of substantially cylindrical form with an axial opening through it from end to end, means for securing rigidly and hermetically a cable introduced into one end thereof to said body portion, a cap closing said axial opening at the opposite end thereof, said cap provided with a petticoat extending beyond the walls of the said body portion, and an orifice

formed in the wall of the body portion beneath the protection of the petticoat formed upon said cap, substantially as described. 30

2. A three-piece terminal for an electric cable, consisting of a casing, a thimble, and a cap, said casing being of substantially cylindrical form with an axial opening through it from end to end and said casing formed 35 of insulating material integral and homogeneous throughout, externally petticoated, and provided with two lead out orifices giving communication within the said axial opening and arranged upon opposite sides 40 of such external petticoat, said thimble being adapted to be connected hermetically to a cable sheath and closing at one end the axial opening through said casing, and said cap closing at its opposite end the axial 45 opening through said casing, substantially as described:

In testimony whereof, I have hereunto set my hand.

CHARLES W. DAVIS.
